(57) **CLAIM**

The ornamental design for a screed component, as shown and described.

DESCRIPTION

FIG. 1 is a front, top, left perspective view of a screed component showing the new design;

FIG. 2 is a rear, bottom, right perspective view thereof;

FIG. 3 is front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a front, top, right perspective view thereof, in an environment of use.

The broken lines show portions of a screed component that form no part of the claimed design.

The broken lines seen in FIG. 9 are for the purpose of showing environmental structure, and form no part of the claimed design.

1 Claim, 9 Drawing Sheets
